UNITED STATES PATENT OFFICE.

BENJAMIN FRANKLIN ALLEN, OF CHICAGO, ILLINOIS.

NECKTIE-SUPPORTER.

1,223,229.

Specification of Letters Patent.

Patented Apr. 17, 1917.

Application filed March 27, 1914. Serial No. 827,705.

To all whom it may concern:

Be it known that I, BENJAMIN F. ALLEN, a citizen of the United States, residing at Chicago, in the county of Cook and State of Illinois, have invented certain new and useful Improvements in Necktie-Supporters; and I do hereby declare the following to be a full, clear, and exact description of the invention, such as will enable others skilled in the art to which it appertains to make and use the same.

This invention relates to necktie supporters, and one of the principal objects of the invention is to provide a necktie supporter of simple construction which will spring over the head of the front collar button so that the device cannot be readily detached by accident, and said supporter being provided with an upwardly inclined point or prong for engaging the tie, and said point or prong having an enlargement below the terminal point which will prevent the accidental disconnection of the tie from the hook.

Another object of the invention is to provide a necktie supporter of simple construction which will hold the tie or scarf from either vertical or lateral movement relatively to the front collar button.

These and other objects may be attained by means of the construction illustrated in the accompanying drawings, in which,

Figure 1 is a front elevation of a portion of a turndown collar and having a necktie supporter made in accordance with this invention connected to the front collar button,

Fig. 2 is a side elevation of the necktie supporter connected to the shank of a collar button of ordinary construction,

Fig. 3 is a similar side elevation showing the scarf or tie connected to the supporter,

Fig. 4 is a front elevation of the supporter showing the initial position of the supporter relatively to the head of the collar button before the supporter is pulled down on the shank of the button to engage the same by the spring action of the side members of the key hole slot.

Referring to the drawing, the numeral 1 designates a turndown collar, and 2 is the head and 3 the post or shank of an ordinary front collar button.

The necktie supporter is formed preferably of slightly resilient wire of the desired gage, and comprises a key hole slot

formed by bending the wire to provide the enlarged portion 4 and the contracted portion 5. The enlarged portion 4 of the key hole slot is slightly larger than the head 2 of the button, so that the button head must be sprung through the enlarged portion 4, and the two members 6—6 at the sides of the contracted portion 5 of the slot engage the shank 3 of the collar button with sufficient friction to prevent the supporter from moving upward or becoming detached.

One terminal of the wire forming the supporter is bent around the supporter at the base of the enlarged portion 4 of the key hole slot, as shown at 7, and the other terminal of the wire is first bent inward as shown at 8, and then inclined upwardly and terminating in a prong 9. Immediately below the prong and in a position nearly opposite the projecting portion 7 is an enlargement or hump 10, said two elements serving to provide a contracted portion so that when the tie is connected to the hook a portion of the tie will be crowded down in the loop 11 of the hook and prevented from accidental detachment by the contracted portions 7 and 10.

From the foregoing it will be obvious that a necktie supporter made in accordance with this invention, when sprung over the head of a collar button and pulled down so that the side members 6 firmly engage the shank of the button, that the necktie when engaged with the hook and a portion of the tie confined in the loop 11 underneath the projecting portions 7 and 10, will not permit either the necktie supporter to move upon the collar button or the tie or scarf to move upon the supporter.

The invention is simple in construction, can be manufactured at low cost, is reliable and efficient for its purpose, can be quickly connected to the shank of a collar button, and cannot be readily detached by accident.

Slight changes may be made in the various features of the invention without departing from the spirit and scope of the same as defined in the claim.

What is claimed is:—

A necktie supporter comprising a continuous length of wire, bent upon itself to form keyhole slots adapted to receive a collar button, one end of the wire being of greater length and bent rearwardly and

upwardly in spaced relation thereto for forming a prong to engage a necktie, said prong having a hump adjacent its free end, and the other end of the wire being bent 5 forwardly and around the rearwardly extending portion of the other end of the wire to form a hump for coöperation with the first mentioned hump, providing a re-

stricted portion to retain the necktie upon the prong.

In testimony whereof I affix my signature 10 in presence of two witnesses.

BENJAMIN FRANKLIN ALLEN.
